J. C. YOUNG,
METHOD AND APPARATUS FOR VULCANIZING,
APPLICATION FILED JAN. 17, 1921.

1,390,005.

Patented Sept. 6, 1921.

SECTION A-B

FIG. 2

FIG. 3

FIG. 1

WITNESS.S

8 W. H. Owen

INVENTOR

John Cresswell Young

UNITED STATES PATENT OFFICE.

JOHN CRESWELL YOUNG, OF WASHINGTON, DISTRICT OF COLUMBIA.

METHOD AND APPARATUS FOR VULCANIZING.

1,390,005.

Specification of Letters Patent. Patented Sept. 6, 1921.

Application filed January 17, 1921. Serial No. 437,975.

To all whom it may concern:

Be it known that I, JOHN CRESWELL YOUNG, a citizen of the United States, residing at Washington, District of Columbia, 5 have invented a new and useful Method and Apparatus for Vulcanizing, of which the following is a specification.

My invention relates to a method and apparatus for vulcanizing rubber, plastics, etc., 10 in any form, but is for use more particularly in the building, re-building, re-treading and repairing of automobile tires and tubes.

An object of the invention is to provide a 15 method of vulcanizing in which the absorption of moisture by the fabric of the article being vulcanized may be avoided.

Another object of the invention is to provide a method of vulcanizing in which dry 20 heated air, either alone or mixed with the gaseous products of combustion or other gases, may be used directly to maintain the articles to be vulcanized at the desired temperature.

25 A further object of the invention is to provide a new and useful vulcanizing pot.

A still further object of the invention is to provide a new and improved vulcanizing pot in which the absorption of moisture by 30 the fabric in the articles being vulcanized may be avoided.

A further object of the invention is to provide a new and improved vulcanizing pot in which heated air, either alone or mixed 35 with the gaseous products of combustion or other gases, may be used directly to maintain the articles undergoing vulcanization at the desired temperature.

With these and other objects in view the 40 invention consists in the method and apparatus described in the following specification and defined in the claims. The various features of the invention are illustrated in the accompanying drawings in which:

45 Figure 1 is a vertical sectional view of a vulcanizing pot embodying a preferred form of the present invention;

Fig. 2 is a sectional plan view taken on the line A—B of Fig. 1; and

50 Fig. 3 is a plan view of the cover for the vulcanizing pot shown in Fig. 1.

As will be seen in Fig. #1, the tank portion of the pot (1) is of conical shape, the sides converging toward the top. Attached 55 to the platform (2), also shown in Fig. #2, is an inverted cone (3) filled with asbestos (4). Supporting the platform are four

legs (5) attached with bolts also affording support for the tank. The burner (6), preferably gas, is placed directly beneath the 60 opening (7) of the conical shaped bottom (8) of the tank. The burner (6) should be placed sufficiently low beneath the opening (7) so that the flame of burner (6) will mount to only one-third the distance between the top of burner (6) and the opening (7). This is to allow sufficient draft space for admission of heated gases and emission of the cooled gases and to allow absorption of the necessary oxygen from the 70 atmospheric air to cause combustion of the gas of burner (6). Attached to the inner surface of the outer tank is a reflector (9) covering entire inner surface of the tank above the platform (2). Flange (10) of the 75 cover (11) affords an air-tight joint, the cover attached only by friction to the tank. An inverted cone (12) attached to the cover (11) is for the purpose of forming a deflecting baffle for the vulcanizing agent (dry 80 atmospheric air). Upon cover is shown clamp (13), one of several which may be attached for clamping portions of inner tubes to the hot surface of the cover for vulcanizing repairs. Thermometer (14) attached to the 85 cover, with mercury pot above a small hole in the cover, allows registering of the temperature contained within the pot. The upper cavity (17) of the pot is for accommodation of the articles to be vulcanized, 90 while the lower cavity (18) is what may be termed a mixing chamber for the heated air.

In Fig. #2, section "A—B," plan view of the platform (2), upon which are placed articles to be vulcanized, may be seen. Supporting flange of the legs (5) and supporting angle (19) of the legs are illustrated. The channel (15) is for passage of the heated air from beneath into the vulcanizing cavity (17). In Fig. #3, plan view of the 100 cover, location of the handles (16) and tube clamp (13) and thermometer (14) is shown.

Operation of the pot is in this manner, the cover (11) is removed and the articles to be vulcanized placed upon the platform (2), 105 the cover replaced and the burner (6) lighted. The heat produced causes an induced draft of atmospheric air beneath the sides of the tank, and forced draft of hot air through the opening (7) of the bottom (8). The 110 hot air forced through the opening strikes the point of the cone (3) and is deflected downward, forming a swirling motion and is then precipitated upward and downward

several times in the mixing chamber (18). The agitated motion causes uniform mixture and uniform temperature of the air which then passes through the channel (15), upward and inward, deflected and reflected by the reflector (9) and cone (12).

The arrows illustrate the draft of the air. In the upper, or vulcanizing cavity, a uniform temperature of any desired vulcanizing strength is maintained through the draft of hot air ascending and warm air descending. Heated air naturally ascends to the highest point of a container. To secure a uniform temperature in the entire vulcanizing chamber (17), the top or cover of the vulcanizer is preferred unequipped with a vent, this causes the heated air upon reaching the top to be precipitated downward causing a swirling mass of hot and warm air, thereby attaining a uniform temperature at all heights of the chamber (17). Through poor draft or in cases where it is necessary to place the article to be vulcanized within a cement or plaster cast containing water a small vent 25 may be placed in the top or cover to allow escape of moisture or form a draft provided the vent is regulated to maintain the proper motion of the heated gases.

With but slight attention, the workman 30 maintains suitable and uniform temperature by increasing and decreasing the flow of gas and referring to the thermometer (14). To relieve the workman a thermostatic gas control may be attached to the burner.

35 An ordinary cure or vulcanizing process with the use of this pot requires but one hour and thirty minutes, including opening and closing of the pot. Simplicity of operation of this pot as against previously used steam 40 pots, which require steam boiler, attention of an engineer and a mechanic for opening and closing, forms a great advantage in economical operation.

The vulcanizing temperature may range 45 from 290° to 320° Fahrenheit and the period required to perform a cure or process of vulcanization will range from forty (40) minutes to one hour and thirty (30) minutes.

50 Although the shape and design of this vulcanizing pot is given as a vertical, circular tank of conical shape, desired results may be produced if the tank is constructed square, oblong or portional round, provided principals of illustrated cavity design are used. 55 Also where the design of the tank is shown to be of one piece with cover fitting upon extreme top, the tank may be made in sections, divided into halves, thirds, etc., with the cover securely attached to the upper portion of the tank. Entire upper portion of 60 the tank under this arrangement may be equipped and operated with a counter balance weight and tackle, that it may be raised overhead by a single mechanic. This plan 65 would be unnecessary with construction of

a small pot, but will be found advantageous in construction of pots for large manufacturing use. Whereas shape of the tank (1) is shown conical, converging toward the top in construction of a small pot sides of the 70 tank may be entirely vertical. After setting up the pot for operation it is advisable to cover the outer portions with asbestos cement or some form of non-heat conducting 75 insulating compound or substance to prevent loss of heat and to prevent overheating the space containing the pot.

Suggested material for use in construction of the kettle is given specifically, for 80 which, as will be noted substitute material may be used to advantage under some circumstances. While it is suggested that the circular tank, cover and bottom be of sheet iron; concrete, clay and similar substitutes or other metals may be used in their construction depending upon the locality in which manufacture occurs. For marketing purposes sheet iron would be preferable.

85 The reflector (9) may be of any bright reflecting metal or any reflecting substance such as bronze may be applied to the inner surface of the outer tank, the purpose of which is to reflect the heat rays toward the center of cavity (17) causing a uniform temperature at all times.

90 The platform (2) illustrated as of wood may be constructed of any non-heat conducting material of sufficient strength to support a weight of 300 pounds, or may be constructed of iron or other metal insulated 100 with covering composed of asbestos or other non-heat conducting substance.

95 While the cone (3) attached to the under surface of platform (2) may be constructed of any substantial material, it is recommended 105 constructed of sheet iron, and may be filled with dry asbestos (4) or other non-heat conducting dry substance. This filling is for the purpose of preventing conduction 110 of heat from point of cone (3) to the platform (2).

115 The legs (5) while recommended constructed as illustrated of wrought iron, may be constructed of any other material of sufficient strength to individually support a weight of 500 pounds.

Whereas burner (6) is recommended to be 120 of illuminating gas type, oil fuel burner, or in barren localities a coal or wood smolder fire located beneath the opening (7) of the tank bottom (8) will produce the desired results. Electric coil heaters placed beneath the opening (7) or in cavity (18) will also produce the desired results if current may be obtained at a low rate.

125 This vulcanizing pot while affording medium by which dry heated atmospheric air may be used in accomplishing vulcanizing process of rubber and plastics, also affords improvement in vulcanizing pots as affects 130

original cost and cost of operation. Manufactured from the recommended material, the cost of this type of vulcanizer as against cost of steam plants of any form, will 5 amount to only one-tenth the cost of the most reasonable priced steam outfit. In operation of this pot both in simplicity of opening and closing of the pot and in assembling the articles to be vulcanized and in 10 the operation of the pot as pertains to the heat agent, is economy accomplished. The direct heat as against indirect heat of steam pots affords operation of this vulcanizing pot for one-tenth the cost of operation of 15 steam pots.

Use of dry heated air as a vulcanizing agent affords the only vulcanizing process performing satisfactory work as affects re-treading and rebuilding of old pneumatic 20 tires in a single cure or vulcanizing process.

I am aware that prior to my invention pots for the purpose of vulcanizing rubber and plastics with steam generated by boiler and pots heated with electricity have been 25 made. I, therefore, do not claim invention of the pot method of vulcanization; but:

I claim:

1. A method of vulcanizing which comprises confining the article to be vulcanized 30 in a vulcanizing chamber and causing a current of air mixed with the hot gaseous products of combustion to pass into said chamber and contact with the article to effect the vulcanization thereof.

35 2. A method of vulcanizing which comprises burning a fuel, mixing the hot products of combustion with air and bringing said hot gaseous mixture into direct contact with the article to be vulcanized to effect the vulcanization thereof.

40 3. A method of vulcanizing which comprises confining the article to be vulcanized in a chamber having an opening in one wall thereof, heating the air adjacent said 45 opening to cause a current of heated air to rise through said opening into said chamber and contact directly with the article to be vulcanized to effect the vulcanization thereof.

50 4. A method of vulcanizing which comprises confining the article to be vulcanized in a vulcanizing chamber having an interior surface having high heat reflecting characteristics, burning a fuel out of contact with said article, uniformly mixing the 55 hot gaseous products of combustion with air, and bringing the hot gaseous mixture uniformly into contact with said article to effect vulcanization thereof.

60 5. A method of vulcanizing rubber tires which comprises burning a fuel out of contact with said tires, mixing the hot gaseous products of combustion with air, passing 65 said hot gaseous mixture upwardly in a stream around said tires and thereafter de-

flecting said upward stream downwardly into direct contact with said tires.

6. A vulcanizing apparatus which comprises a burner, a mixing and combustion chamber, and a vulcanizing chamber adjacent 70 said mixing chamber with an opening connecting said chambers.

7. A vulcanizing apparatus comprising a vulcanizing chamber having a cover, and an inverted cone presenting a heat reflecting 75 surface attached to the inner side of said cover.

8. A vulcanizing apparatus comprising a vulcanizing chamber having a cover, the inner surface of the side walls of said chamber having high heat reflecting characteristics, and a member attached to the inner side of said cover and extending downwardly to present a heat reflecting surface. 80

9. A vulcanizing apparatus comprising an 85 upright vulcanizing pot having an opening in its bottom, a heater located beneath said opening, and a partition within said pot forming a support for the articles to be vulcanized and dividing said pot into an 90 upper vulcanizing chamber and a lower mixing chamber with an opening connecting said chambers to permit the hot gases to rise from the mixing chamber into the vulcanizing chamber.

95 10. A vulcanizing apparatus comprising an upright vulcanizing pot having an opening in its bottom, a heater located beneath said opening, a partition forming a support for the articles to be vulcanized and dividing 100 said vulcanizing pot into an upper vulcanizing chamber and a lower mixing chamber with an opening connecting said chambers, and heat insulating material on the under side of said partition.

11. A vulcanizing apparatus comprising an upright vulcanizing pot having an opening in its bottom, a heater located beneath said opening, and a partition forming a support for the articles to be vulcanized and 110 dividing said vulcanizing pot into an upper vulcanizing chamber and a lower mixing chamber with an opening connecting said chambers, the side walls of said vulcanizing chamber having an interior surface having 115 high heat reflecting and poor heat conducting characteristics.

12. An apparatus for vulcanizing which comprises an upright vulcanizing pot, a partition dividing said vulcanizing pot into a 120 mixing chamber and a vulcanizing chamber with an opening connecting said chambers, said partition being insulated to prevent the substantial direct transfer of heat therethrough from said mixing chamber to 125 said vulcanizing chamber, and means for burning fuel and mixing the hot products of combustion with air in said mixing chamber.

JOHN CRESWELL YOUNG.
